UNITED STATES PATENT OFFICE.

EDWARD E. GREEN, OF SAN FRANCISCO, CALIFORNIA.

DESIGN FOR A HEEL-REST.

• 56,809.

Specification for Design. Patented Dec. 28, 1920.

Application filed October 16, 1919. Serial No. 331,212. Term of patent 14 years.

To all whom it may concern:

Be it known that I, EDWARD E. GREEN, a citizen of the United States, residing at the city and county of San Francisco, State of California, have invented a new, original, and ornamental Design for a Heel-Rest, of which the following is a specification, reference being had to the accompanying drawing, forming part thereof.

Figure 1 represents a new and ornamental design for a heel rest constructed in accordance with my invention.

Fig. 2 is a side elevation of the same.

What I claim and desire to secure by Letters Patent is:—

The ornamental design for a heel rest as shown.

EDWARD E. GREEN.
